UNITED STATES PATENT OFFICE.

GEORGE C. BLACKMORE AND LAWRENCE R. BLACKMORE, OF NEWARK,
NEW JERSEY.

RADIATOR.

SPECIFICATION forming part of Letters Patent No. 448,630, dated March 24, 1891.

Application filed June 11, 1890. Serial No. 355,106. (No model.)

To all whom it may concern:

Be it known that we, GEORGE C. BLACKMORE and LAWRENCE R. BLACKMORE, citizens of the United States, residing at Newark, Es-
5 sex county, New Jersey, have invented cer-
tain new and useful Improvements in Radi-
ators, fully described and represented in the
following specification and the accompanying
drawings, forming a part of the same.

10 The object of this invention is to furnish
an efficient hot-water radiator of neat appear-
ance and adapted to be easily set up in its
operative position.

15 The invention consists partly in a particu-
lar construction for the radiator-sections and
partly in certain details of construction.

20 In the annexed drawings, Figure 1 is a side
elevation of a radiator embodying our inven-
tion; Fig. 2, an elevation of one of the inter-
mediate sections taken at right angles to the
position shown in Fig. 1, and Fig. 3 is an end
elevation of the entire radiator. Fig. 4 is a
25 central vertical section of the radiator; and
Figs. 5 and 6 are central vertical sections,
taken at right angles to the position shown
in the preceding figure, of one of the end and
intermediate sections, respectively. Fig. 7 is
30 a sectional elevation of the inlet-valve, and
Fig. 8 a plan of the same. Fig. 9 is a trans-
verse section of the lower portion of one end
section with one of the feet applied thereto.
Fig. 10 is a transverse section on line x x in
Fig. 6.

35 The radiator is shown herein comprising
two end sections and four intermediate sec-
tions having their heads connected together
by means of nipples in the usual manner; and
it is evident that the number of intermediate
sections may be increased or diminished to
40 alter the area of heating-surface of the radi-
ator without changing its operation. Each
radiator-section comprises two vertical col-
umns a, connected at the top and bottom by
the horizontal heads a' and a², respectively.
45 The end section, to which the hot-water sup-
ply pipe is connected, is provided with an in-
let-tube t, intermediate to such vertical col-
umns a and extending between the heads a'
and a².

50 In order to insure the introduction of the
hot water into the top of the radiator, a tube

t', fitted to the interior of the inlet-tube t, is
provided at one end with a bush t², which is
screwed into a suitable aperture in the bot-
tom of the head a², with the tube t' projecting 55
a little above the top of such head. By this
means the lower end of the inlet-tube t is
closed from the lower head, and the hot water
on entering passes directly to the upper end
of the inlet-tube t past the valve v, whence it 60
is distributed in the other sections of the radi-
ator through the nipples n'. The supply-
pipe p is screwed into the bush t² in order to
connect the same with the radiator. In each
of the other sections the water columns are 65
connected between the heads a' and a² by a
series of inclined tubes b, through which the
water has a free circulation from one column
to the other without interrupting its down-
ward flow in its passage to the outlet-pipe p, 70
which is applied to the section at the oppo-
site end of the radiator.

The inlet-valve consists of the usual disk
v, beveled on its rim to fit a conical seat s,
formed at the top of the inlet-tube t, and hav- 75
ing its stem v' threaded to engage a threaded
sleeve m, through which such stem passes.

To avoid the exposure of the stuffing-box
beyond the surface of the section it is formed
within a cup c, having an external thread at 80
the top fitted to an aperture in the top of the
head a', and having the sleeve m projected
upwardly from its bottom. A guard n is at-
tached to the upper end of the valve-stem and
provided with a knob o to turn the latter in 85
actuating the valve, and such guard is formed
with a cylindrical shell fitted to the interior
of the cup c to prevent the accumulation of
dust and dirt within the cup c and to prevent
its being ground into the joints between the 90
valve-stem and the sleeve m in the operation
of the device.

As shown in Figs. 1, 3, and 9, the extremi-
ties of the heads a² of the end sections are
provided with rabbets h, having grooves g 95
therein parallel to the lower corners of the
heads. The feet i are provided with sockets
fitted to the rabbeted portions of the heads
a², and with ribs j within such sockets to en-
gage the grooves g. By such construction the 100
feet are readily detachable, and may be re-
moved from the radiator to render the fittings

below the same accessible in connecting and disconnecting the supply and return pipes.

For convenience in setting up the radiator in place we apply thimbles to the lower ends 5 of the supply and discharge pipes, which are provided with flanges or floor-plates at their lower ends, and are also provided with internal screw-threads for the pipe-connections to the boiler. Such thimbles are connected to 10 the supply and discharge pipes by means of couplings *r*, of special construction for easy application and removal.

The object of the inlet-tube *t* is to avoid 15 the marring of the appearance of the radiator by an external tube extending from the floor to the top of the radiator, at which point it is desirable to feed the hot water in order to secure a good circulation throughout the several sections.

20 Having thus set forth our invention, what we claim herein, and desire to secure by Letters Patent, is—

1. In a radiator-section, the combination, with the columns *a a*, united at the ends by 25 the heads *a'* and *a²*, of the series of inclined tubes *b*, as and for the purpose set forth.

2. The combination, with a series of radiator-sections, each consisting of the columns *a*, heads *a'* and *a²*, and inclined tubes *b*, of an 30 end section consisting in the vertical columns *a a*, united at the ends by the heads *a'* and *a²*, and the intermediate tube *t*, connecting the heads and having an inlet-connection at 35 its lower end, as and for the purpose set forth.

3. The combination, with a series of radia-

tor-sections, each consisting of the columns *a a*, heads *a'* and *a²*, and inclined tubes *b*, of an end section consisting in the vertical columns *a a*, united at the ends by the heads *a'* and *a²*, the intermediate inlet-tube *t*, and the 40 tube *t'*, connecting the heads and formed integral therewith, fitted to the interior of the same and extended through the lower head *a²* to connect with the supply-pipe, substantially as shown and described. 45

4. The combination, with a radiator-section having an upright inlet-tube *t*, provided with the valve-seat *s* at its upper end, of the valve *v*, with threaded stem *v'*, the cup *c*, applied to the upper end of the section and provided 50 with the upwardly-projecting sleeve *m*, threaded internally and inclosed therein, and the guard *n* and knob *o*, applied to the upper end of the valve-stem, as and for the purpose set forth. 55

5. The combination, with a vertical radiator-section having rabbets formed in its lower end with grooves *g* therein, of feet *i*, having sockets fitted to the rabbets in the head *a²* and provided with ribs *j* to engage the grooves 60 *g*, substantially as shown and described.

In testimony whereof we have hereunto set our hands in the presence of two subscribing witnesses.

GEORGE C. BLACKMORE.
LAWRENCE R. BLACKMORE.
